UNITED STATES PATENT OFFICE.

JAMES W. KNOBLOCK, OF ELMIRA, NEW YORK, ASSIGNOR TO AMERICAN LA FRANCE FIRE ENGINE CO. INC., OF ELMIRA, NEW YORK, A CORPORATION OF NEW YORK.

DESIGN FOR A RESPIRATOR.

57,528.

Specification for Design.

Patented Apr. 12, 1921.

Application filed March 26, 1920. Serial No. 369,102. Term of patent 7 years.

To all whom it may concern:

Be it known that I, JAMES W. KNOBLOCK, a citizen of the United States, residing at Elmira, in the county of Chemung, in the State of New York, have invented a new, original, and ornamental Design for a Respirator, of which the following is a specification, reference being had to the accompanying drawing, forming part thereof.

In said drawing:

Figure 1 is a front view of my design for respirator.

Fig. 2 is a side view of the same.

Fig. 3 is a rear or inside view of the same.

I claim:

The ornamental design for a respirator as shown.

JAMES W. KNOBLOCK.
